HARRY E. THOMPSON, OF DETROIT, MICHIGAN, ASSIGNOR TO UNIVERSAL COOLER CORPORATION, OF DETROIT, MICHIGAN, A CORPORATION OF MICHIGAN.

CYLINDER-CAP CONSTRUCTION FOR COMPRESSORS.

Application filed February 15, 1926. Serial No. 88,244.

This invention relates to improved cylinder cap construction for compressors especially compressors used in power refrigeration. It is a well known fact that one of the great difficulties in power refrigeration is the loss of the refrigerant due to leaks. It is one of the objects of the present invention to provide a cylinder cap construction of great thickness so as to form a bridge. This not only cuts down the possibilities of the cap distorting, but lessens the number of bolts necessary to secure the cap to the cylinder block. Furthermore, this construction provides an unrestricted chamber above the valve and thereby lessens the accumulation of heat instant to restricted and tortuous passage.

Another important improvement is the construction of the cylinder head partition of relatively thin sheet metal. This requires no machining, and in contrast to the prior art constructions which ordinarily employ thick castings, this diminishes the accumulation of heat in the head and keeps the compressor working at cooler temperatures. It also eliminates the necessity of a projection of the piston head to pass into the valve opening for the purpose of lessening the clearance between the partition head and the top of the cylinder. This will be more fully explained hereinafter. In the drawings:

Fig. 1 is a vertical section of the compressor.

Fig. 2 is a plan view of the same.

Fig. 3 is a section on the line 3—3 of Fig. 2.

Fig. 4 is a fragmentary section taken at right angles to the showing of Fig. 1.

Fig. 5 is a section taken on the line 5—5 of Fig. 1.

Fig. 6 is a section taken on the line 6—6 of Fig. 1.

Fig. 7 is a perspective view of the head, and part of the valve cage.

It seems unnecessary to letter and call attention to the customary moving parts of a compressor such as the crank shaft, connecting rod, and piston rings on the cylinder. These are all clearly shown in the drawings. The charge is drawn in through the port *a*, circulates through the chamber *b*, depressions *c* in the sides of the piston and into the chamber *d*.

It will be obvious as the piston pushes

down, the valve *e* rises from its seat and permits the charge to pass through the valve head of the piston. When the piston movement is reversed this valve is thrown against its seat and the charge is compressed in the chamber above the piston until the pressure accumulates sufficiently to lift the light spring *f* that holds the valve *g* upon its seat. This valve can lift about a few thousandths of an inch when it encounters the resistance of the heavy spring *h* which bears against the shoulder *g*. This resists further opening of the valve unless an incompressible fluid accumulates between the piston head and the valve. This results in creating hydraulic pressure. This is heavy enough to lift the spring and blow out the accumulated lubricant, or other liquid. Clearance between the partition head *i* and the head of the piston is only a few thousandths of an inch.

It has been customary heretofore to use relatively heavy partitions, or heads, from three-eighths to one-half inch. As far as I am aware, these have always been castings and the valve caging is ordinarily in the form of a boss, or ring, which is an integral part of such casting. Very often the springs that hold a valve on its seat abut against the inside of the cylinder cap. It is the object of the present invention to provide not only an improved heavy bridging cap, but also provide an improved sheet metal cylinder head or partition. To this end I employ a piece of sheet metal stock of preferably one-eighth inch thickness. This does not require any machining to make it smooth enough to take the gaskets *j*, nor to get an even clearance space above the end of the piston.

In order to provide a valve cage, studs *k* with reduced ends are riveted over in countersunk holes in the head. They are then welded in place to secure them better and to seal the joint against all leakage. I shall not go into the details of valve cage construction, as that is a separate invention which is in my co-pending application, Serial No. 88,243, filed February 15, 1926, for obviously it could be used with a different kind of cylinder head, such as a casting of considerable thickness.

In place of the usual flanged cylinder cap in which the bolts are turned into the flange immediately above the cylinder head, I uti-

lize a heavy cylinder cap which really has no flanges at all. But in which the bolts, as shown in the Fig. 3, pass through substantially the entire side of the cylinder cap 5 casting. This makes a heavy bridge, as it were, spanning the compression chamber above the cylinder head. This, I find very advantageous, for the lighter castings of the type having the usual bolt flanges very often 10 distort slightly and produce leaks around the gasket, which cause no end of trouble. With that type of cylinder cap it is ordinarily thought necessary to use six bolts so as to counteract this bowing tendency of the 15 flanges; by my cylinder cap, or bridge construction, four bolts are all that are necessary. Furthermore, my bridge construction of the cap brings the bolt heads up to a point where they may be given more clearance from 20 the body of the casting and it is possible to use wrenches on the bolt heads that can not be utilized when the bolts lie close in to the body of the cap.

It will also be apparent that the compression chamber *m* can be made somewhat larger in diameter with the bolts carried high, as shown in Fig. 3, than will be possible where a flange construction is employed with the bolts the same distance apart between centers. It is desirable to get this 30 compression chamber as large as possible so as to prevent the accumulation of heat in the compressor walls.

A similar advantage follows from the use 35 of the relatively thin sheet metal cylinder head, for of course, this member is directly in the path for hot gases, and where it is three or four times as large in cubical capacity it accumulates a proportionally greater 40 amount of heat units to the detriment of the compressor operation. Furthermore, in these thick cast metal heads the port covered by the valve *g* being comparatively deep, it is found desirable to have a plug on the end of 45 the piston which is carried into this port to lessen the clearance space above the piston head to get the proper efficiency and not leave part of the gases in the cylinder to re-expand after work has been done upon them, 50 and to be recompressed at each stroke. I have found that where this port is only one-eighth inch deep that the amount of gas left in the cylinder at the end of each stroke is sufficiently negligible so that this factor may 55 be neglected and the plug omitted in the head of the piston. This is a desirable feature in building the compressors as it does away with the troublesome problem of very accurate machining of the cylinder heads 60 and proper locating of the pistons in respect thereto, so that the plug will always be properly centralized with the port. This problem, by my construction, is entirely eliminated.

65 Still another feature is that the post con-

struction, which I have described as being the design of the cage, is particularly appropriate with this sheet metal cylinder head, and the post construction permits an open valve cage. This materially increases 70 the capacity of the compression chamber for ordinary sizes of cylinder caps, and thereby, more or less minimizes the problems due to the accumulation of heat.

The cylinder head is provided with the 75 cooling fins *n*, which are designed for, and calculated to dissipate the heat accumulating in the cap.

What I claim is:

1. In a compressor, the combination of a 80 cylinder, a piston reciprocating in the cylinder, a cylinder cap, and a relatively thin cylinder head secured between the cap and the cylinder end and spaced from the cap, said head provided with a valve port which 85 communicates directly with the space between the head and the cap, a valve mounted on the head for guarding the port, this port being of such limited depth, due to the thinness of the cylinder head, as to be practically a negligible factor in the clearance 90 space left between the piston and the valve.

2. In a compressor the combination of a 95 cylinder having a reciprocating piston therein, a cap for the cylinder which has thick side walls and which is secured to the cylinder by bolts passing through such side walls, a head for the cylinder consisting of a thin sheet of metal which is disposed between the cylinder body and the cap, this 100 thin head being spaced from the top portion of the cap by reason of the thick side walls of the cap, valve mechanism disposed between the cap and the head and which is supported entirely by the said head and independent of the cap, including a valve 105 which seats directly on the head, and the said head being provided with a port which is closable by the valve.

3. In a compressor, the combination of a 110 cylinder having a reciprocating piston therein, a cap for the cylinder, means for securing the cap to the cylinder, a head for the cylinder consisting of a thin sheet of metal which is disposed between the cylinder and the cap, this thin head being spaced from the top portion of the cap, valve mechanism disposed 115 between the cap and the head which is supported entirely by the said head and which is independent of the cap, and the said head being provided with a port which is closable by the valve, the clearance between the valve 120 and the piston being practically negligible in the operation of the machine by reason of the thinness of the cylinder head.

4. In a compressor, the combination of a 125 cylinder block, a piston reciprocating therein, a cap boltable to the end of the cylinder, a sheet metal head of relatively small thickness secured between the cap and the end 130

of the cylinder block and having an outlet port of relatively small depth, and valve cage posts supported by the thin head around said opening on the head and having each a 5 hermetically sealed joint with said head.

5. In a compressor, the combination of a cylinder block, a piston reciprocating therein, a cap boltalbe to the end of the cylinder, a sheet metal head of relatively small 10 thickness secured between the cap and the end of the cylinder block and having an outlet port of relatively small depth and valve cage posts supported directly by the thin head about the outlet port and welded 15 to the sheet metal head.

6. In a compressor, the combination of a cylinder block and a cap bolted thereto comprising a casting whose sides are compara-

tively thick—the thickness constituting the major part of the depth of the casting to 20 form bridging members between the top of the cap and the cylinder block that tend to prevent the distortion or bowing of the cap.

7. In a compressor, the combination of a cylinder block, a cap, a cylinder head bolted 25 between the cap and the end of the block, said cap rising at its sides directly upwardly from the cylinder head for the major portion of its depth, and then forming a central boss of reduced diameter to complete the 30 depth of the cap, and bolts passing through the upwardly rising portions thus formed at the sides of the cap.

In testimony whereof I affix my signature.

HARRY E. THOMPSON.
